UNITED STATES PATENT OFFICE.

WELLINGTON E. JENKINS, OF PITTSBURG, KANSAS.

CONTAINER FOR BLASTING CHARGES.

Application filed July 20, 1926. Serial No. 123,776.

This invention relates to blasting devices and more particularly to a container for blasting powder adapted to be inserted in the hole caused by the explosion of a so-called 5 "springer" after the latter is fired at the bottom of a drill hole.

The present invention is particularly useful in connection with the surface mining of coal. In such a mining operation, after the 10 overburden is removed from the coal, a drill hole is made substantially to the depth of the 15 knot of the vein of coal after which a small piece of dynamite called a "springer" is fired at the bottom of the drill hole for 20 the purpose of blasting an opening or pocket in which to pour blasting powder for the blasting of the coal. Dynamite is not a practical explosive for use in blasting coal inasmuch as it pulverizes the coal and decreases the value thereof. Blasting powder 25 has been found to be the proper explosive to be used for this purpose, and is in common use in blasting coal in surface mining operations. Where the coal is wet after the 30 springer is fired, the powder must be hurriedly poured into the hole and exploded before it becomes wet. This operation is unsatisfactory for the reason that it is dangerous to prepare a charge of blasting powder in a drill hole in which a springer has 35 been fired, without giving the drill hole time to cool off, and when the charges are placed in a wet hole, about 20 per cent of the charges thus prepared do not explode due 40 to the fact that the powder becomes wet or damp. Where the charges fail to fire, the holes must be drilled out at considerable expense and with more or less danger.

An important object of the present invention is to provide a water-proof container for the blasting powder which is adapted to be inserted in the hole caused by the firing of a springer, without danger 45 of the powder becoming wet.

A further object is to provide a water-proof container of the character mentioned whereby a number of charges may be placed in openings caused by the successive firing of springers and the charges connected to be 50 fired simultaneously, the device being adapted to prevent moisture from coming in contact with the powder over an indefinite period of time.

A further object is to provide a rubber or 55 similar container for blasting powder including a tubular neck portion having an

enlarged bulb at its lower end, and to provide a metal or similar tube in which the entire container is adapted to be arranged when it is to be introduced into a hole caused 60 by the firing of a springer, the metal tube being removed after the enlarged bulb is in position at the bottom of the hole, whereupon dirt or the like may be tamped into the hole to close the same prior to firing 65 the charge.

A further object is to provide a container for the blasting powder having means associated therewith for holding the usual explosion cap. 70

Other objects and advantages of the invention will become apparent during the course of the following description.

In the drawings I have shown one embodiment of the invention. In this showing: 75

Figure 1 is a perspective view of the device.

Figure 2 is a side elevation of the same showing the metal retaining tube in position, parts being broken away, 80

Figure 3 is a side elevation of the device in position ready to be fired, and

Figure 4 is a detail sectional view of the lower end of the retaining tube, showing a portion of the container in position. 85

Referring to the drawings the numeral 10 indicates the charge container as a whole preferably formed of rubber or other suitable flexible material, including an upper neck portion 11 and a lower enlarged bulb 90 portion 12. The neck portion is reduced as at 13 and is provided with an upper tubular portion 14 having an open end as shown. The bulb portion 12 is provided with a preferably integral tubular portion 15 which 95 is adapted to receive an explosion cap 16 of the usual type having wires 17 leading thereto. The container is adapted to be surrounded by a rigid metallic or similar tube 18, as shown in Figure 2. When the explosion cap and blasting charge are in position, the tubular portion 15 and the reduced portion 14 of the neck are adapted to be tied with strings or the like 19 to prevent moisture from entering these portions of the device. 100

The operation of the device is as follows:

The usual hole is drilled into the vein of coal after which the usual springer is fired at the bottom of the drill hole thus causing 110 an enlarged opening to be formed at the bottom of the drill hole. An explosion cap 16

is introduced into the smaller tubular portion 15 and the end thereof is tied with the string 19, the wires 17 projecting upwardly adjacent the neck 10. The device is then ready to be introduced into the retaining tube 18, the bulb 12 being collapsed or squeezed together to permit its insertion within the tube. The upper end of the neck is left projecting from the tube 18, and the neck 11 is filled with a suitable charge of blasting powder. The string 19 is then tied around the reduced portion 14 of the neck, whereupon the device is ready for introduction into the drill hole. The lower end of the tube 18 is inserted into the drill hole whereupon the operator may shake the tube 18 to dislodge the bulb 12 from the lower end of the tube. This action causes the powder to flow downwardly into the bulb, whereupon the tube 18 may be withdrawn and the emptied neck of the container permitted to fall into the lower part of the hole as shown in Figure 3. The drill hole then may be filled with dirt or the like, as shown in Figure 3. It will be obvious that the bulb 12 then will be arranged within the enlarged opening formed by the firing of the springer. The device then may be fired in the usual way by initially firing the explosion cap 16. Since the container protects the blasting charge from moisture, it will be apparent that one of the devices may be left in position until additional containers are arranged in other drill holes, whereupon the several sets of wires 17 may be connected together and to a suitable source of current to permit all of the charges to be fired simultaneously. It will be apparent that the container is adapted to provide a water-proof shielding means to prevent the absorption of moisture by the blasting charge.

It is to be understood that the form of the invention herewith shown and described is to be taken as a preferred example of the same and that various changes in the shape, size and arrangement of parts may be resorted to without departing from the spirit of the invention or the scope of the subjoined claims.

I claim:

1. A device of the character described comprising a water-proof flexible container having a tubular neck portion provided with an open upper end and a lower bulb portion formed integral therewith, a relatively small tubular member carried by said bulb portion and adapted to receive an explosion cap, and a rigid retaining member in which said container is adapted to be arranged.

2. A device of the character described comprising an integral flexible rubber container including an upper tubular neck portion provided with an open upper end, a lower bulb portion communicating therewith and a relatively small tubular member carried by said bulb portion and adapted to contain an explosion cap, and a rigid retaining tube in which said container is adapted to be arranged, said retaining tube being slightly larger in diameter than the neck portion of said container and substantially smaller than the bulb portion thereof.

In testimony whereof I affix my signature.
WELLINGTON E. JENKINS.
